UNITED STATES PATENT OFFICE

NIKOLAUS SCHMITT AND OTTO SCHMITT, OF KUPPERSTEG, GERMANY

ELECTRIC MINE FIRING DEVICE

Application filed October 20, 1928, Serial No. 313,684, and in Germany November 21, 1927.

The invention relates to electric detonators for firing blasting charges.

Electric fuses for firing such charges have previously been proposed comprising an electric conductor so secured in a plug of insulating material arranged in the metal casing or cap of the fuse that a spark for igniting the explosive charge is produced between the end of the conductor extending into the cavity of the detonator not only when the insulation of the conductor is good but also when it is defective, or even (provided the conductor is comparatively short) if it is not insulated at all.

Low frequency currents which have hitherto only been employed for operating such fuses have necessitated that at least one of the two conductors must be very well insulated. This has the disadvantage of making the cost of production relatively high, particularly as the wires employed for detonators are destroyed in the blasting operation. Moreover when the fuses, as is frequently the case are laid in moist or damp places a further disadvantage is produced by the insulation becoming deteriorated, so that current leakage occurs sufficient to prevent or hinder the operation of the fuse.

With a view to obviating these disadvantages a method of firing detonators according to the invention consists in employing high frequency alternating current as the ignition current of the order of 50,000-4,000,000 cycles per second as employed for example in wireless telegraphy and telephony and produced by any known high frequency generator.

The invention is based on the knowledge that if a thin wire connected with a source of high frequency current is brought with its end remote from that at which the high frequency current is supplied towards another conductor, neither earthed nor connected to the source of current, a spark is produced between the opposed ends of the conductors so long as the conductor which is being approached has sufficient natural self-capacity.

It is found that high frequency currents flowing in a conductor between the source

of current and detonator are discharged at the end of the conductor extending into the cavity of the detonator not only when the insulation of the conductor is good but also when it is defective, or even (provided the conductor is comparatively short) if it is not insulated at all.

A further advantage obtained by using high frequency ignition currents is that the metal casing of the fuse need not be earthed or connected by a special conductor with the source of current. It is only necessary to connect the conductor embedded in the insulating material of the fuse to the one pole of the high frequency current generator, and the use of a second conductor connected to the other pole of the source of current or to ground is unnecessary, thus greatly cheapening and simplifying the operation. For long distances a metal wire insulated by a thin lacquer coating may be used, whilst for short distances bare conductors may be used.

The value of employing high frequency ignition is still further seen by the fact that a detonator at the end of a bare metal wire can still be detonated even if the wire is lying in about three feet of water, or if the paper-covered wire is secured to trees or walls and the detonator is about 600 yards from the source of current, there being no need in either case to earth the detonator or connect it by an additional wire to the source of current.

In the accompanying drawings:

Figure 1 illustrates the principle employed in igniting fuses or detonators according to the invention.

Figure 2 is a section through a practical embodiment.

Figures 3 and 4 are, respectively, a sectional and a side elevational view, partly broken away, of a constructional modification.

In Fig. 1 the current conducting wire 1 of relatively small cross-section terminates below within a suitable priming or detonating pellet 2. The metal member 3 containing the fulminate 5 is in light contact with the pellet or fusing mass. Upon a high-frequency

current being sent into the wire 1, the mass 2 is fused.

In the embodiment according to Fig. 2 the conducting wire 10 with its priming pellet 20 is surrounded by an insulating substance 4 arranged within the upper portion of the metal shell 6. The lower portion of the latter contains the fulminate 5. For placing the pellet 20 into electrical contact with the shell 6 a metallic connection must be made between the two, which, by way of example, may be in the form of crumpled metal foil 7, (Fig. 2) or loose metal powder, or a metal strap may be inserted contacting with the shell wall 15 and supporting the pellet. An effective contact is also obtained by providing the insulating substance 4 at its lower portion with a coating 8 of graphite, aluminum or the like metal powder (Figs. 3 and 4).

20 In experiments which have been carried out a high frequency alternating current of the order of 1,000,000 cycles per second has been employed. The potential of the current employed in the experiments ranged from 4,500-25,000 volts. It is to be understood however that the necessary potential for firing the detonating composition of the explosive cartridge would travel according to the construction and dimensions of the priming mass at 30 the end of the conductor within the cartridge.

In the manufacture of electric firing devices the cost of the wire runs up to 60% of the total, so that any reduction in the amount of conducting material is of great moment, 35 and in the present instance this saving in wire amounts to practically 50%, since only a single conducting wire is required. In addition to the other advantages set forth it may be said that the connecting-up of the shots, owing to the simplified construction of the device, can readily be attended to even by an 40 unskilled operator.

What I claim is:—

1. An electric mine fuse for high-frequency 45 operation, comprising a single conducting wire of relatively small cross-section designed for the passage of a high frequency current and adapted to be connected to one pole of a source of high frequency current, a combustible pellet enclosing the discharge end of the wire in such manner that a spark gap is formed between the extreme point of the wire and the contact point of support of the pellet, a metal shell, a fulminate in the bottom portion of this shell, and an insulating member in the upper portion thereof, and current-conducting means interposed between, and in contact with, said pellet and said shell and forming one terminal of the spark gap for coaction with said point of the wire forming the other terminal of said gap.

2. An electric mine fuse for high-frequency 55 operation, comprising a single lead-in wire of relatively small cross-section, a combustible pellet enclosing the discharge end of the

wire in such manner that a spark gap is formed between the extreme point of the wire and the contact point of support of the pellet, a metal shell, a fulminate in the closed end portion of the shell, an insulating member in the open end portion of the shell, and a current conducting metal coating on the lower portion of the insulating member.

3. In a detonator for detonating an explosive charge by means of a high frequency current, a metal body, a thin metal conductor insulated from the metal body, said conductor being of restricted cross-sectional dimensions for passage of a high frequency current therethrough and being adapted for connection to a source of high frequency current, a discharge terminal at the end of said conductor and having a cross-section not exceeding the cross section of the conductor, an ignition mass surrounding the discharge terminal, a conductor powder covering the ignition mass, and a conductive layer of tinsel-like substance conductively connecting the said powder and the metal body.
